Primary Examiner — Susan E Krakower*(74) Attorney, Agent, or Firm* — Davis Wright Tremaine LLP(57) **CLAIM**

The ornamental design for a carafe lid, as shown and described.

DESCRIPTION

FIG. 1 is a perspective view of a carafe lid of the present invention;

FIG. 2 is a first side view thereof;

FIG. 3 is a top view thereof;

FIG. 4 is a front view thereof;

FIG. 5 is a rear view thereof;

FIG. 6 is a second side view thereof; and,

FIG. 7 is a bottom view thereof.

The broken lines illustrate environmental structure and form no part of the claimed design.
